MACHINE FOR OPERATING UPON SHOE UPERS

Joseph Fossa, Lynn, Mass., assignor to United Shoe Machinery Corporation, Flemington, N. J., a corporation of New Jersey

Application December 19, 1952, Serial No. 326,948

34 Claims. (Cl. 12—51)

The present invention relates to improvements in a machine for operating upon a shoe upper preparatory for the assembly of an upper with other shoe parts on a last.

The invention is in the nature of an improvement upon the machine for automatically eyeleting and lacing the eyeleted upper shown in the patent to Fossa, No. 2,461,889, dated February 15, 1949, for Machine and Method for Manufacture of Shoes. The machine referred to in general provides a rotatable work supporting turret on which are carried four radially movable workholders each provided with clamping devices for supporting the upper with the lacing margins thereof in an opened-out edge-facing relation and with the counter portion of the upper extending radially inwardly on the workholder toward the axis of the turret. Disposed about the turret are a loading station including means which enable the operator to locate and to secure the upper on the workholder in an exactly predetermined position in accordance with the size and style of the upper to be operated upon. By successive quarter turns of the turret the workholder and upper supported thereon are brought successively into operating relation with an eyeleting machine for inserting eyelets in successive pairs in the upper, and into operating relation with a lacing machine for lacing the eyeleted upper. A further quarter turn of the turret brings the workholder to an unloading station at which the eyeleted and laced upper is released from the workholder preparatory for removal from the machine. The adjustments for size and style of upper imparted to the locating device at the loading station are transferred with the workholder to the eyeleting and thereafter to the lacing machines to cause the eyelets to be properly located and spaced in the upper at the locating station, and to cause the lacings thereafter to be passed accurately through the eyelet holes.

The machine of the Fossa patent referred to is adapted only for the holding of the upper with the lacing flaps in an inside up position for the insertion of invisible eyelets in the upper.

It is a principal object of the invention to provide a novel construction of the work supporting and work transfer devices of the machine which is well adapted for supporting and for presenting a shoe upper to the operating mechanisms with the eyelet flaps in an inside up position for the insertion of invisible eyelets, and alternatively for presenting the shoe upper to the operating mechanisms with the eyelet flaps in an outside up position for the insertion of visible eyelets if so desired.

Other objects of the invention relates more specifically to novel construction of the several work supporting and guiding instrumentalities of the machine and of the operating devices associated therewith to provide for the greater versatility and usefulness of the machine in operating upon shoe uppers.

With these and other objects in view as may hereinafter appear, a feature of the invention consists in the construction and arrangement of the turret and work support as-

2

semblies including the workholders and guideways therefor to provide for adequate counter clearance inwardly toward the axis of the turret for an upper located on the workholder in an outside-up position and with the counter portion of the upper extending downwardly in an encircling position about the work support assembly.

Another feature of the invention consists in the provision of novel and improved upper locating devices under the control of the operator for accurately positioning the upper on the workholder at the locating station, said devices being particularly constructed and arranged to permit the ready positioning of the upper on the workholder in either an inside-up or an outside-up position. In the illustrated construction the pair of locating pins provided for engagement with edged portions of the ankle adjacent the lacing margin and the associated margin engaging fin are mounted on a slide which is loosely supported for sliding movement on the workholder axially of the turret and forms an integral part of the workholder unit. The position of the slide is accurately determined at the locating station by means of adjusting devices under the control of the operator including a gate cam disposed beneath and toward the axis of the turret for engagement with a downwardly and radially inwardly extending follower member associated with the locating slide. The more outwardly disposed separating fin provided for engagement between the lacing margins at the toe end thereof is mounted on a spring plate which is fastened to the turret and extends laterally outwardly beneath the guideway. This spring supported fin is normally maintained in operating position being, however, moved downwardly to an inoperative position upon movement of the turret and workholder therewith to each of the successive eyeleting and lacing stations.

Another feature of the invention consists in the provision of an improved vamp spreading and clamping device which consists of two movable clamping elements, one movable from below and the other from above the level of the supported lacing margins to support portions of the vamp engaged therebetween in a spread-out position, and a toggle mechanism constructed and arranged for effecting a simultaneous movement of the vamp spreader elements to and from the clamping position.

Other features disclosed relate to certain constructions and arrangements of parts in the machine including an improved arrangement of the guiding surfaces thereon to assist in the transfer of the supported upper on the turret to successive stations, to better support and to guide outlying portions of the clamped upper when moved outwardly from the turret for each of the eyeleting and lacing operations, and to further support the downwardly extending counter portion of the upper when mounted on the machine for the insertion of the visible eyelets during that portion of the operation when the eyeleted and laced upper is released and is removed from the machine.

The several features of the invention consist also in the devices, combinations and arrangement of parts hereinafter described and claimed which, together with the advantages to be obtained thereby, will be readily understood by one skilled in the art from the following description taken in connection with the accompanying drawings, in which:

Fig. 1 is a fragmentary plan view of an automatic machine for eyeleting and for lacing the eyeleted shoe upper illustrating particularly the work supporting and transfer assembly of the machine including the turret and four workholders;

Fig. 2 is a detail view in elevation on an enlarged scale of the trip mechanism indicated in plan in Fig. 1 controlled by the downward movement of the upper vamp spreader for throwing the machine into operation;

Fig. 3 is a fragmentary view on an enlarged scale of

the turret mechanism shown in Fig. 1 illustrating one of the workholders with an upper clamped therein, a second workholder in its open position and a third workholder partially broken away to show underlying parts;

Fig. 4 is a detail view in side elevation on a still larger scale illustrating particularly the toggle control and toggle trip mechanisms for the vamp spreaders with the toggle straightened and the spreaders in the clamping position;

Fig. 5 is a view somewhat similar to Fig. 4 but with the toggle connection broken and the vamp spreaders fully retracted to their open position;

Fig. 6 is a fragmentary view of the vamp spreader hinge looking from the left of Fig. 5;

Fig. 7 is a view in front elevation of the turret and workholder assembly partly sectioned on a section line passing through the turret axis, two of the workholders disposed respectively at the eyeleting and unloading stations being shown;

Fig. 8 is an isometric view looking from below illustrating portions of one of the workholders, and the shoe upper locating slide with the locating pins and fin slidably mounted on the workholder;

Fig. 9 is a fragmentary detail plan view of one of the workholder assemblies partly in section to illustrate particularly the lace measuring unit associated therewith;

Fig. 10 is a sectional view in elevation of one of the workholder assemblies shown in Fig. 7 looking outwardly from the axis of the turret;

Fig. 11 is a somewhat fragmentary plan view of the work supporting turret casing including the cover for the turret casing, the locating device, the feed slides at each of the eyeleting and lacing stations, and certain of the upper guiding and shielding surfaces provided in accordance with the invention;

Fig. 12 is a somewhat fragmentary plan view of certain of the driving and control devices including the turret drive and the mechanism for transferring the shoe upper size adjustment to each of the eyeleting and lacing machines;

Fig. 13 is a somewhat fragmentary view looking from the right of the eyeleting machine toward the turret axis to illustrate the raised position of the eyeleting and lacing machines relatively to the base and the turret, and more particularly the relation of the present disclosure to the more complete disclosure of Fossa Patent No. 2,461,889;

Fig. 14 is a fragmentary view of the eyeleting machine looking radially outwardly from the turret in order to illustrate the shoe upper supporting and guiding devices associated with the eyeleting machine feed slide;

Figs. 15 to 21, inclusive, are views illustrating a modified form of the invention in which vamp spreaders provided with hook elements are caused to engage with and remove stray, overlying portions of the lining material from the operating zone of the eyeleting and lacing mechanisms;

Fig. 15 being a fragmentary plan view of the machine illustrating particularly the work supporting and transfer assembly including the turret and two of four work holders mounted therefrom;

Fig. 16 is a detail view in side elevation of one of the work holder assemblies at the loading station with the parts in position as the clamp spreaders are closed causing micro-switch control rod 226 to be depressed to start the machine;

Fig. 17 is a somewhat fragmentary plan view of the pivoted vamp spreader unit at the eyeleting station, the parts being shown in positions taken with the actuating arms 462 and 482 engaged with the respective vamp spreaders;

Fig. 18 is a view similar to Fig. 17 in which the actuating arms have moved the vamp spreader 488 and the associated under-vamp spreader, not shown, outwardly to

clear the shoe lining material from the path of the eyelet inserting mechanism;

Fig. 19 is a view taken at the completion of the eyeleting operation at which the eyeleting mechanism has been moved outwardly to the starting position, but leaving the vamp spreaders and actuating arms also in their extended positions;

Fig. 20 is an elevation looking from the rear of the mechanism shown, for example, in Fig. 15 for causing the vamp spreader actuating arms to be moved to the actuating position; and

Fig. 21 is an enlarged detail view in elevation, partly in section, looking from the lower side of Fig. 19 illustrating particularly the manner in which overlying portions of the shoe lining are pulled away from the location of the first eyelet pair in the upper.

Referring to the drawings, the general arrangement of the improved machine disclosed for performing related eyeleting and lacing operations upon a shoe upper

20 is generally indicated in the plan views, Figs. 1, 3, 11, and 12 and in the partly sectioned side view, Fig. 7, only so much of the machine, however, being shown as is believed necessary to illustrate the connection of the present invention therewith. For a more detailed disclosure of the machine, reference may be had to the Fossa Patent No. 2,461,889, above referred to. In the present disclosure, the base of the machine is generally indicated at 50 and includes a cylindrical casing 52 within which is mounted an indexing work supporting turret. 30 The turret provides support for four workholders 132 which are mounted on guideways 131 extending radially outward from the turret at 90° angles from one another. At the front side of the machine, there is provided a locating station which comprises a locating mechanism 35 generally indicated at P for the assistance of the operator in locating and clamping successive uppers on the workholders. At the remaining stations proceeding in a counterclockwise direction around the turret there are provided an eyeleting mechanism generally indicated at 40 I, a lacing mechanism generally indicated at L, and a fourth station between the lacing and loading station to which the workholding clamps are released.

The indexing turret, which is in certain respects similar and is supported and actuated in a manner similar to that of the Fossa patent referred to, comprises a vertically disposed hollow pivot shaft 54 which is rotatably supported in a sleeve bearing member 62 formed at its lower end with an outwardly extending flange secured by screws 64 to a bed plate 66 which forms a rigid portion of the machine frame. At its upper end the turret shaft 54 carries a large circular disc 68 secured to rotate with the shaft 60. In the present construction the disc 68 is utilized to provide a support for a newly added turret structure hereinafter to be described. In each quadrant of the disc 68 on the underside thereof there is provided an aperture 69 for engagement with a detent plunger 70 which acts to positively locate the turret in each successive indexed position. A cover 71, comprised of two semicircular cover members secured to the top of the turret casing 52 and overlying the disc 68, serves to protect the mechanism housed in the casing from accumulations of dirt or other extraneous matter. Immediately inside the cover 71 is a fixed ring bearing member 72 which is secured against movement with relation to the turret casing 52 by means of two radially extending support bars 73 (see Figs. 7 and 11).

The turret is arranged to be driven through connections which include a Geneva mechanism and a drive shaft having a worm gear connection with the Geneva mechanism, as indicated in Fig. 12, together with a clutching and braking mechanism and an electric motor, not here specifically described. The driving connections shown in Fig. 12 comprise specifically a star wheel 74 secured to the hollow turret shaft 54 beneath the bed plate 66

and having formed thereon four radially disposed slots 76 which are engaged in turn by a roll 78 mounted on a Geneva driving arm 80 on a vertically disposed drive shaft 82. A worm wheel 84 secured to the lower end of the drive shaft 82 meshes with a worm 86 on the forward end of a drive shaft 87 which extends rearwardly through the base of the machine to the motor and clutching devices above referred to.

Further in accordance with the disclosure of the Fossa patent above referred to, the illustrated machine is provided with a size adjustment control mechanism adapted for effecting adjustment of each of the several cooperating mechanisms for locating, supporting and operating on shoe uppers in accordance with the spacing of the eyelets of the shoe uppers being operated upon. The size adjustment mechanism comprises, generally, a manual control lever 88 (see Fig. 12) which is secured to and extends upwardly from a supporting pivot shaft 89. The manual control lever 88 is adjusted by the operator in accordance with the size of shoe upper about to be placed in the workholder. The setting of the manual control is operative to effect an adjustment of the shoe upper locating mechanism at the loading station and at the same time controls the position of a traveling cam which transfers this adjustment to the feed mechanism associated with each of the eyeleting and lacing machines in turn in timed relation to the indexing movement of the turret. While the mechanism for transferring the size adjustment to the eyeleting and lacing machines is fully described in the Fossa patent above referred to and forms no part of the present invention, portions of this mechanism, as illustrated in Fig. 12 of the drawings, include a cam drum 90 and four axially shiftable wing cams 92 mounted thereon, these parts being driven in timed relation from the turret through gearing which includes a bevelled gear 94 on pivot shaft 96 which carries the cam drum 90, a vertically extending counter shaft 98, a bevel gear 100 which meshes with bevel gear 94, and a pair of gears (not shown) which are mounted in meshing relation respectively on the shaft 98 and turret shaft 54.

The wing cams 92 are presented in succession by the rotation of the drum 90 to each of four stations which correspond respectively to the loading, eyeleting, and lacing stations, and to a fourth inactive station to which the work supports are presented by the rotation of the turret shaft 54. At the first of these stations, each wing cam 92, each time it passes through said station, is positioned axially of the drum 90 by means of a cam engaging lever 101 controlled by the size adjustment manual control lever 88. During the next indexing movement of the turret shaft 54 and drum 90 therewith the wing cam is locked in its adjusted position by means, not here specifically shown, and is brought into engagement with a feed control follower element, also not here shown, which extends beneath the drum and is connected with the vertically disposed link 102 indicated in Fig. 13 associated with the eyeleting machine. Thereafter during another indexing movement of the turret shaft 54 and drum 90 the wing cam, still locked in adjusted position, is brought into engagement with a feed control follower mechanism associated with the lacing mechanism to transfer the adjustment for size in accordance with the setting of the hand lever 88 first to the eyeleting station and then to the lacing station in synchronism with the transfer of the associated work support and upper mounted thereon. The connections controlled by the cam 92 for adjusting the feed mechanism associated with the lacing mechanism as best shown in Figs. 12 and 13 include a cam follower 104 carried on an arm 106 on a rock shaft 108, another arm 110 on the rock shaft being connected through a vertically disposed link 112 with one arm of a lever 114 mounted to turn in the fixed pivot 115 and the other arm of the lever 114 being

connected by means of a link 116 with the lacing machine feed adjusting mechanism.

Adjustment of the size adjustment control lever 88 operates through appropriate connections to effect a corresponding adjustment in the position of the locating device at the loading station. These connections as generally indicated in Figs. 11 and 12 include a rotatable shaft 118 which is connected by means of a rack and pinion, not specifically shown as forming no part of the present invention, with the size adjustment control lever 88. The shaft 118 is connected through a universal connection 119 with a rotatable link 120 which is in turn connected through a universal joint 122 with a pinion supporting shaft 124 rotatably mounted in a bracket 126 mounted on the front side of the turret casing 52. A pinion 127 on shaft 124 meshes with a rack formed in a locating pin adjustment slide 128 hereinafter more fully to be described.

In carrying out the present invention the turret and workholders associated therewith are constructed and arranged to receive the opened-out upper either with the inside surface of the lacing margins facing upwardly or alternatively with the outside surface of the lacing margins facing upwardly on the workholder, and to present the clamped upper in either of these positions at each of the several operating stations of the machine. In the illustrated machine the shoe upper is loaded onto the workholder at the loading station with the encircling heel portion thereof toward the axis of the turret and with the toe portion of the upper extending outwardly. When the upper is placed on the workholder with the inside surface of the lacing margins facing upwardly, the encircling heel portion is disposed around the movable clamping member and the lace measuring finger. In accordance with the invention the turret assembly including turret, workholders, and the several operating controls for the workholders are particularly constructed and arranged to provide adequate clearance so that the heel portion of the upper may readily be slipped radially onto the workholder with the outside surface of the lacing margins facing upwardly and with the encircling heel portion of the upper extending downwardly in an encircling position about the base portion of the workholder and associated guideway.

With the present construction the turret is provided with an upward extension or hub 129 which is rigidly secured to the turret shaft 54 and disc 68 and is formed with a table top 130 which is of substantially smaller diameter than the disc 68 previously referred to (see Figs. 3 and 7). At its lower end the hub 129 is externally supported by the sleeve bearing member 72. The table top 130 provides support for four guideways 131 (see Fig. 3) which extend radially outwardly from the turret at 90° angles to one another to receive the respective workholders 132. It will be noted that the guideways 131 are each formed of two rails spaced from one another to form an open slot therebetween and that radially extending channels 133 are cut into the table top 130, forming inward extensions of the slots provided between the rails of the respective guideways. A second channel 134 is cut inwardly into the periphery of the table top 130 in parallel relation to each channel 133 is adapted to receive the shank portion of the lower vamp spreader 148 when the vamp spreader is in its downwardly projecting open position, and the workholder has been retracted on its support as shown in Fig. 5.

Each workholder 132 of the illustrated construction, see Figs. 7 and 8, comprises a generally U-shaped member having outwardly flanged edges 135 forming guides which ride under the recessed edges of the rail guideway 131, and two parallel sets of upwardly extending resiliently mounted pins 136 (see Fig. 7) which form the lower relatively stationary elements of a clamping device for engaging the two adjoining edge portions of the upper. Each of the stationary clamping elements is formed toward its outer end with a laterally extending tab 137

which is particularly adapted to engage with and support the tongue portion of the shoe upper in a folded-over out-of-the-way position for the outside-up position of the upper on the workholder as shown, for example, in Fig. 7. Said tabs 137 are similar in shape to and underlie tabs 158 shown in plan in Fig. 3 attached to the cooperating upper jaws 146 of the clamping device as herein-after described. The workholder 132 is formed with a vertically disposed post socket 138 (see Figs. 7 and 8) which projects downwardly from the closed end of the workholder adjacent the axis of the turret and is arranged to support for vertical adjustment therein a measuring bar support post hereinafter to be described. The socket 138 projects downwardly through the aperture formed by the channel 133 and separated rails of the guideway 131 and is freely movable therein with the workholder on the guideway 131.

As in the Fossa patent referred to, the workholders are normally maintained in a fully retracted position on their guideways 131, that is, a position toward the axis of the turret. However, at each of the eyeleting and lacing stations the workholder is operatively connected with a feed slide which acts to impart a stepped feeding movement to the workholder and upper mounted thereon outwardly into operating relation with the respective eyeleting and lacing mechanisms, and thereafter to return the workholder to the normally retracted position on the turret preparatory to a further indexing movement of the turret. In the illustrated construction an improved means is provided for normally locking the several workholders in their retracted positions, which will not interfere with the loading and unloading of the upper onto the workholder or with the transfer and feeding movements of the workholder and shoe upper supported on the turret for either of the alternate outside-up and inside-up positions of the upper on the workholder. As best shown in Fig. 7, the downwardly extending socket 138 associated with each workholder has secured thereto a downwardly extending cam follower member 139 which is adapted to ride in a circumferential slot 140 formed in the upper face of the bearing ring 72. At each of the eyeleting and lacing stations a radially disposed gateway 141 is provided from the slot to permit the workholder to be moved freely outwardly on its guideway 131. In accordance with the disclosure of the Fossa patent above referred to, each of the eyeleting and lacing machines is provided with a feed slide which is operatively connected with the workholder presented at the particular station, and which thereafter acts to feed the workholder into the respective machines and then to return the workholder to its retracted transfer position. The feed slide associated with the eyeleting machine is indicated at 142 (see Fig. 7) having a bifurcated outer end 143 notched for locking engagement with correspondingly formed notches 144 in the workholder. The feed slide associated with the lacing machine is indicated at 145 (see Fig. 11) similarly formed with a bifurcated and notched outer end portion for engagement with the workholders presented successively thereto by the indexing movement of the turret.

Each workholder 132 as shown, for example, in Fig. 7, has mounted thereon a pair of movable work clamping jaws 146, a pair of vamp spreaders 147, 148, and a lace measuring or alotted bar 149. The work clamping jaws 146 comprise a pair of lever arms which are supported intermediate their length on a pivot shaft 150 on the workholder 132 (see Figs. 3 and 7), and are connected at their rear ends to identical toggle links 151 which are pivotally connected to toggle links 152 rotatably supported on a laterally extending pivot pin 153 at the rear end of the workholder 132. The toggle links 152 are connected to turn as a single unit by a strap 154 arranged to be engaged by an actuating lug 155 secured to the upper end of an axially movable control shaft 156 which is preferably connected to be moved downwardly by a treadle control, not here specifically shown.

Downward movement of the control shaft 156 causes the lug 155 to engage and depress the strap 154 to straighten the toggle links 151, 152 and thereby to effect a simultaneous movement of the clamping levers to clamping position. A small tension spring 157 connected between one of the clamping levers and work support tends normally to maintain the clamp in its open or disengaged position. Each of the clamping jaws 146 is provided with a horizontally disposed tab 158, shown for example in Fig. 3, which projects laterally outwardly from the lacing slit and is particularly intended to engage with and support the tongue portion of a shoe upper in a folded-over out-of-the-way position for the inside-up position of the upper. For the outside-up position of the upper, the horizontally disposed tabs 158 assist in holding in a flattened-out position adjacent portions of the upper which may not be adequately engaged by the vamp spreader.

The work clamping jaws 146 are released prior to the final indexing movement which transfers the work support with the eyeleted and laced upper held thereon back to the loading station by means of an automatic release mechanism which is substantially similar to corresponding mechanism in the Fossa patent. The clamp release mechanism acts during the third indexing movement of the work support, i. e., during the indexing movement which serves to transfer the work support away from the lacing mechanism to a position at the left side of the machine, as indicated, for example, in Fig. 7. Clamp release plungers 162 are provided one for each work support journaled to slide in vertical drills in the turret beneath the straps 154 of the clamp toggle connections, so that upward movement of any one of the plungers will cause the head thereof to engage and move the cooperating strap 154 upwardly to break the toggle connection, and thereby to release the toggle clamp. Substantially at the completion of each indexing movement of the turret the plunger 162 associated with the workholder which has been moved to the position at the left of the loading station, is moved upwardly into engagement with the strap 154 to break the clamp toggle links 151, 152 by the action of a slide 164 (see Fig. 7) supported for vertical movement in a relatively stationary guideway formed in a sleeve member 166 keyed to the fixed sleeve bearing element 62. The connections for raising the slide 164 and the contacting plunger 162 therewith (see Figs. 7 and 12) comprise a face cam 168 formed on a cam plate 170 on the drive shaft 82 of the Geneva motion, and a cam follower lever 172 secured to a rock shaft 174. Another arm 176 secured to the rock shaft 174 is connected by a link 178 with a lever arm 180 secured to a rock shaft 182 to which is also secured an actuating arm 184 having a roll 186 for engagement with a traverse slot in the slide 164.

A feature of the present disclosure consists in the provision of an improved device for spreading and supporting the vamp portion of the upper in a flattened-out condition during the work transfer, eyeleting and lacing operations. As best shown in Figs. 3 to 6, inclusive, upper and lower vamp spreaders 147, 148 are associated with each workholder, the vamp spreaders 147, 148 being each formed and arranged to swing about a common pivot 190 and connected for related movements to engage simultaneously against opposite faces of the vamp portion of the upper. Each of the arms 147, 148 is provided at its outer end with a relatively slender, curved lateral extension 192 which for the engaging position of the vamp spreader passes across the vamp portion of the upper immediately beyond the end of the lacing slit. It will be noted that each extension 192 has a cut-away portion 194 which serves to provide additional space for the performance of the eyeleting and lacing operations along the length of the lacing slit in the upper. The vamp spreader arms 147, 148 are connected to move toward and away from each other as a unit by means of a

toggle connection consisting of a toggle link 196 and a toggle link 198 connected together by a pivot pin 200. The link 196 is connected at its free end to an arm 202 extending rearwardly from the base of the vamp spreader 147, and the free end of the toggle link 198 is similarly connected to a rearwardly extending arm 204 formed integrally with the vamp spreader 148. For the further control of the toggle connection, the toggle connecting pivot pin 200 is provided at one end with a cam roll 206 which rides in a U-shaped slot 208 formed in a block 210 secured to the workholder 132. A weighted arm 212 forming a right angle extension of toggle link 198 provides a convenient manual means for straightening the toggle when desired. In order to move the vamp spreader unit to its closed position, the operator pushes the vamp spreader 147 downwardly. The weighted arm 212 which is thus caused to move from the position of Fig. 5 to the position of Fig. 4 will have sufficient momentum to move the toggle links to a past center locking position.

The vamp spreader is automatically released at the same time that the clamping jaws clamping the upper in position are opened by means of connections actuated from the work clamp toggle connections. The operating connections referred to include a rock shaft 214 carried on a bracket 216 fixed on the workholder. An upwardly extending arm 218 secured to the rock shaft 214 is arranged to be engaged by an upwardly extending lever arm 220 mounted on pivot 153 to turn as a unit with the toggle link 152. A leftwardly extending hook-shaped arm 222 on the rock shaft 214 engages a short right angle extension 224 of the vamp spreader toggle link 196. The breaking of the toggle links 151, 152 to release the clamping jaws causes the arm 220 to be rocked leftwardly from the position shown in Fig. 4 so that rock shaft 214 is turned positively in a counterclockwise direction so that the arm 222 acting on the lateral extension 224 positively moves the vamp spreader toggle connection from the straightened position of Fig. 4 to the fully collapsed position of Fig. 5 in which the vamp spreaders 147 and 148 have been moved to their open release position.

The downward movement of the upper vamp spreader 147 by the operator to the upper clamping position is utilized to close a machine start microswitch to place the machine in operation. The switch referred to is indicated at 225 in Figs. 1, 2, and 11 and forms a part of the machine starting circuits, being similar both in construction and in general mode of operation with the corresponding switch illustrated in the Fossa Patent No. 2,461,889, above referred to. The microswitch 225 is fixedly mounted on the side of the turret casing 52. With the present construction a novel construction is employed for controlling the operation of the microswitch 225 from the vamp spreader arm 147 which consists in the provision of an upwardly extending contact pin 226 which is slidably supported in a sleeve member 227 arranged to turn on pivots 228. A spring 229 (see Fig. 1) tends to swing the contact pin 226 in a counterclockwise direction to the limiting position of Fig. 2 in which the sleeve member 227 is engaged against an adjustable stop screw 230. In order to render the contact pin 226 operative to actuate the microswitch, the upper vamp spreader 147 is arranged to extend beyond the edge of the lower vamp spreader 148 so that as the upper clamp is moved downwardly by the operator, it can be sprung somewhat beyond its normal closed position to engage against the upper end of the contact pin 226 which is thus caused to move axially downwardly to actuate the microswitch 225. It will be noted that the sleeve member 227 on the contact pin 226 is pivotally supported on the pins 228 so that as the indexing of the turret subsequently takes place, the post can be knocked aside by the leading end of the lower auxiliary clamping member as the indexing movement of

the turret carries the work assembly from the loading to the eyeleting station.

A novel mechanism is provided for supporting and for adjusting the position of the measuring bar 149. 5 The mechanism shown has the advantage that it is readily adjustable by the operator in accordance with the lacing requirements of the particular upper being operated upon, is compact, and is so arranged on the workholder to permit the shoe upper, including the quarter portion 10 thereof, to be placed in the desired location on the workholder with either the inside or outside surface of the eyelet flaps facing upwardly as may be desired. As best shown in Figs. 7, 9, and 10, the lace measuring bar 149 is mounted on an arm 234 which is pivotally supported 15 for angular adjustment on a horizontally extending bracket 235 mounted on a vertically adjustable post 236 which is axially shiftable in the socket 138 forming an integral part of the workholder 132. The bracket 235 carries a transversely disposed pivot pin 237 on which 20 the arm 234 is mounted to turn. Two arcuate scales 238 and 240 are formed in a vertically disposed plate 241 mounted from the upper end of the post 236 for indicating respectively the position of angular adjustment of the arm 234 and the position of vertical adjustment of the 25 lace measuring bar assembly including the post 236. For determining the angular position of the lace measuring bar 149, the arm 234 is extended rearwardly across a portion of the plate 241 opposite the scale 238 and is held in adjusted position in relation thereto by means of 30 a small spring detent 242 which is spring pressed against a series of serrations 244 on the plate 241 (see Fig. 7). Vertical adjustment of the lace measuring bar 149 bodily is effected by means of a manually operated adjusting lever 246 which, as best shown in Fig. 7, is supported to turn on a pivot pin 248 supported by the scale plate 241 and an auxiliary supporting plate 250 secured to the lace measuring bar carrying post 236. The adjusting lever 246 extends across the portion of the plate 241 opposite the scale 240 and is held in adjusted position with relation thereto by means of a spring detent 252 which frictionally engages with a series of serrations 254 formed on the plate 241. A laterally extending arm of the vertical 35 adjusting lever 246 is connected by means of a link 256 with a lug 258 on a vertical plate 260 secured to the 40 post 236.

Further in accordance with the invention, the lace measuring bar 149 is mounted to be readily removable to permit a plurality of such lace measuring bars of different lengths to be interchangeably employed in the machine for the eyeleting and lacing of different types of shoe. It has been found, for example, that with the blucher type of shoe in which the shoe is assembled on a last with the sides of the lacing slit in substantially 50 spread parallel relation, a long measuring bar is required which extends over the outer fin (Fig. 7) in order to measure the length of the lacing which is preferably placed in the eyelets formed at the throat of the lacing slit. With a bal type of shoe, on the other hand, in which the upper is assembled on a last with the sides of the lacing slit close together at the base and spread out toward the upper end, a relatively short lace measuring 55 bar is preferred since no regulation of the lacing inserted through the eyelets at the base of the lacing slit is required and the adjustment of the lace measuring bar is such as to cause the tip of a full-length lace measuring bar to interfere with the outer fin. For ready removal and replacement of the lace measuring bar 149, the bar is provided intermediate its length with a transverse bearing pin 262 which is arranged to drop into a recess or transverse slot 264 formed at the outer end of arm 234. The upper end of the lace measuring bar is holed to receive a pivot pin 266 carried on a spring plate 268, secured to the arm 234 and arranged for the free 60 position of the spring to pass through the hole in the measuring bar and through an aligned hole in the arm 65 70 75

234. The arrangement above described and illustrated is such as to cause the lace measuring bar to rest normally in its adjusted position as determined by the angular adjustment of the arm 234. However, the lace measuring bar is free to move upwardly about the pivot pin 266 in the event that the arm is engaged while portions of the work support are supported thereon during the feeding movements of the work support outwardly at either of the eyeleting or lacing stations of the machine. With the construction shown, all of the pivoted connections are made very loosely so that the lace measuring bar will be free to drop downwardly again to its normal position so that a minimum risk exists that the bar will remain in its raised position and be brought into interfering engagement with outlying portions of the lacing mechanism during the indexing movement of the work support away from the eyeleting station and to and from the lacing station of the machine.

The shoe upper is located on the workholder 132 at the loading station P in a manner similar to that employed in the Fossa Patent No. 2,461,889, above referred to. The upper in a flattened-out condition and with the two edges of the lacing slit in adjacent edge-facing relation is placed on the workholder with the counter portion thereof extending inwardly toward the center of the turret. In the event that the upper is placed in position with the inside surface thereof up for the insertion of invisible eyelets, the counter portion of the upper will be positioned above clamping level and will be placed in an encircling position over the movable upper clamping jaws 146 and lace measuring bar 149. If, as contemplated alternatively in accordance with the present invention, the upper is located in a spread-out position with the outside surface of the upper facing upwardly for the insertion of visible eyelets, the heel portion of the upper will be placed in a depending position encircling the lower portion of the workholder 132 and guideway 131. In either event the upper in its spread-out position is moved inwardly on the workholder to a position in which the edges of the ankle portion of the upper adjacent the lacing slit engage against two locating pins 272 (Fig. 3) which are located with relation to the workholder at the loading station in accordance with the setting of the sizing device for the machine. At the same time the edges of the lacing slit are positioned laterally on the workholders by engagement with two fins 274 and 276 arranged to project upwardly through the aperture provided between the parallel clamping surfaces of the workholder.

In accordance with the invention a novel arrangement of the supporting and actuating mechanism for the locating pins 272 and fins 274 and 276 is provided for use in the illustrated machine. A separate shoe upper locating assembly including a pair of locating pins 272 and a lacing margin separating fin 274 is provided with each workholder mounted on a slide 278 for movement freely in a direction radially of the turret along the respective guideway. The slide, including the locating pins 272 and adjacent fin 274 associated with each workholder, is positively located at the locating station by means of a gate cam which is adjustable in accordance with the setting of the upper sizing device. The connections for adjusting the position of the locating pins is constructed and arranged to avoid any possible interference with the positioning of the upper including the encircling heel portion on the workholder in either of its two alternative inside and outside positions. The slide 278, as best shown in Figs. 3, 7, and 8, comprises a bottom plate supported for sliding movement in a guideway formed between the bottom face of the workholder and an H-shaped guide plate 280, a top plate 281, the locating pins 272 which serve also as tie members for fastening together the top and bottom plates of the slide 278, and the fin 274 which is secured directly to the top plate 281. The guide plate 280 is held in spaced relation to the bottom surface of the workholder by means of machine screws 282.

A pin 283 extending downwardly from the underside of the workholder 132 into a slot 284 in the slide 278 serves to limit the movement of the slide in either direction.

The mechanism provided in accordance with the present invention for rendering the size adjustment devices of the machine, previously described, operative to control the position of the slide 278 and locating pins 272 at the locating station comprises a gate cam 285 (Fig. 11) which is supported and arranged to cooperate with a follower member 286 formed on a downwardly bent tongue 287 or cut-out from the plate which forms the slide 278. The gate cam 285, as shown in Figs. 7 and 11, is located closely beneath the turret workholder supporting disk 130 and extends roughly one-quarter of the way around the turret from the unloading station to the left side of the machine to the loading station at the front of the machine. The gate cam 285 takes the form of a horizontally disposed flat plate with converging raised cam edges 290 and is located immediately beneath the workholder supporting disk 130 adjacent the hub portion 129 of the turret so that there is no tendency for the heel portions of an upper mounted on a workholder to be brought into interfering engagement therewith. The gate cam 285 is mounted on the slide 128 previously referred to as forming a part of the upper locating device for movement bodily therewith upwardly and rearwardly of the machine. As best shown in Fig. 11, slide 128 is arranged for forward and back movement in a guideway 291 fastened to a supporting bracket 292 carried on the turret casing 52 (see Figs. 11 and 12) and arranged so that it extends radially inwardly over the turret cover. At its rear end the slide 128 is formed with an arcuate portion 293 which extends to the left side of the machine and terminates in a downwardly extending bar or post 294 to which the gate cam 285 is rigidly secured. As shown in Fig. 7, post 294 is provided with an offset portion which rides on the edge of the stationary ring 72 which thereby serves as an additional supporting and guiding surface for the gate cam assembly.

The outer fin 276 associated with each workholder unit is mounted on a spring plate 300 (see Figs. 3 and 7) which is secured to and projects outwardly from the turret workholder support disk 130 directly beneath the guideway 131.

With this arrangement the outer fin together with its supporting spring plate 300 are so placed that they will not interfere with the placing of the encircling heel portion of the shoe upper in position around these parts. It has been found necessary, however, during the performance of the eyeleting and lacing operations to move the outer fin 276 out of engagement with the clamped upper in order to permit the feeding of the workholder and supported upper outwardly from the turret into cooperative relationship with each of these mechanisms. In order to render the outer fin inoperative at each of the eyeleting and lacing stations, the spring plate 300 is arranged at the eyeleting station to be engaged with a cam 302 (see Figs. 7 and 14) and at the lacing station to be engaged with a similar cam, not shown, so that the spring plate 300 is flexed downwardly, thus moving the outer fin 276 to a depressed inoperative position.

The operation of the work positioning clamping and transfer devices of the machine for the locating of an upper on the workholder at the loading station, the transfer of the workholder to each of the eyeleting, lacing, and unloading stations in turn, and the final removal of the eyeleted and laced upper from the machine is briefly as follows: For each complete operating cycle of the machine the drive shaft 87 of the machine is driven to rotate the vertical drive shaft 82 and the star wheel actuating arm 80 through one full revolution, so that successive indexing turns of a quarter turn each are imparted to the turret shaft 54. Upon completion

of each quarter turn, the eyeleting and lacing mechanisms are rendered operative to perform their respective functions, the workholders being thereafter returned to their retracted positions on the turret, and the machine is stopped. This operation of the driving mechanism and turret is in accordance with the disclosure of Fossa Patent No. 2,461,889, above referred to.

With each indexing movement of the turret, a workholder is brought from the unloading station at the left of the machine to the loading station at the front of the machine. During this movement, the follower 286 associated with the locating pin slide assembly engages with and is brought under the control of the gate cam 285 (see Figs. 8 and 11). Also during this movement of the workholder to the loading station, the upper clamp release cam 168 on the one revolution drive shaft 82 acts through connections which include the follower lever 172, shaft 174, arm 176, link 178, arm 180, shaft 182, and arm 184 (see Fig. 12) to raise the slide 164 and plunger 162 (see Fig. 7) to trip toggle links 151, 162, and thereby to raise the clamping jaws 146 to release the eyeleted and laced upper mounted thereon. A rocking movement of the clamping jaws and toggle links 151, 152 to the broken, shoe upper release position acts through work pin 153 and arm 220 secured thereto, arm 218 engaged by arm 220, rock shaft 214, arm 222, and lateral extension 224, at the same time to move the vamp spreader toggle links 196, 198 to the broken vamp spreader open position of Fig. 5. The completed shoe upper is now ready to be moved from the machine by the operator.

Prior to the placing of a new shoe upper in the machine adjustment of the lace measuring or allocating bar 149 and of the shoe upper sizing device of the machine may be required. In the present construction the height and angle of the measuring bar associated with the workholder at the loading station is readily determined by adjustment of the manual vertical and angle control levers 246, 234 (Fig. 7). Adjustment of the shoe upper sizing device is obtained by adjustment of the upwardly extending lever arm 88 (Fig. 12) which as previously noted acts to control the forward and back position of gate cam 285 (Fig. 11), the slide 278 (Fig. 8) controlled thereby, and sizing pins 272 in accordance with the shoe size of the upper to be operated upon. A corresponding correction is made at the same time in the position of cam lever 101 which in turn controls the position of the associated cam 92 utilized for transferring the size adjustment to the eyeleting and thereafter to the lacing station of the machine.

The operator now places the new upper to be operated upon in position on the workholder at the loading station, the edge portions of the ankle adjacent the upper ends of the lacing flaps being placed against the locating pins 272, and the edges of the lacing flaps being placed in edge-facing relation in engagement with the two locating fins 274, 276. In placing the upper on the workholder with the outside surface thereof facing upwardly for the insertion of visible eyelets, as shown for example in Fig. 7, the heel or quarter portion of the upper is projected longitudinally onto the workholder with the heel in an encircling position around and beneath the stationary jaws of the workholder 132 and the guideways 131 associated therewith.

The operator is now in position to start the machine. The shoe clamp is applied by the operation of the foot treadle which acts to depress the control shaft 156 and lug 155 which engages with the strap 154 to move the clamp toggle 151, 152 to its straightened position. The upper vamp spreader arm 147 is then grasped by the operator, and moved manually downwardly to its clamping position in which it engages with the upwardly extending post 226 of the machine start microswitch 225 to start the machine.

The downwardly swinging movement of the weighted

arm 212 as the vamp spreader toggle links 196, 198 are straightened causes the toggle to be moved to a beyond-center locking position.

Upon movement of the workholder to the eyeleting station as shown in Fig. 7, the outer positioning fin 276, supported on spring plate 300, is moved downwardly to a depressed out-of-the-way position by the engagement of a fixed cam 302 at the eyeleting station with the outer end of the spring plate 300, as shown in Figs. 7 and 14. A similar cam 303 is provided at the lacing station which acts in a similar manner to depress the outer fin 276 prior to the start of the lacing operation on the upper.

A number of auxiliary devices are provided which are well adapted to assist in the guiding and supporting of a shoe upper mounted on the workholder with the lacing margins in either of the two alternative inside-up and outside-up positions above referred to. Auxiliary support is provided for the shoe upper particularly during the period when the clamping devices are released as the workholder returns to the loading station, and for the assistance of the operator in removing the eyeleted and laced upper from the machine by means of a shield or guard 310 (Figs. 5, 7 and 11) which is of generally conical shape and extends slightly more than a quarter of the way about the turret beneath the projecting ways 131 from the unclamping station to the loading station of the machine. The shield 310 provides an auxiliary support for the upper when released by the clamping devices and also acts during the removal of the eyeleted and laced upper from the machine by the operator as a guiding surface to prevent engagement or catching of the heel portion of the upper with the lateral extension 192 associated with the lower vamp spreader arm 148. For this purpose the conical shield is constructed and arranged to permit the vamp spreader arm 148 to be moved downwardly so that the lateral extension 192 thereof is located beneath and is protected by the shield 310, as shown in Fig. 5. The shield 310 is of particular value to support and to guide the heel portion of a shoe upper supported with the outside surface facing upwardly and with the heel encircling the lower clamp and guideway. It will be understood that a similar support may be provided for shielding the heel portion of an upper supported with the inside surface facing upwardly from contact with the upper vamp spreader arm 147 during removal of the upper.

An improved auxiliary supporting device is provided for controlling the outwardly disposed toe portion of the shoe upper which with the illustrated construction may be supported with the eyelet flaps in either an inside-up or an outside-up position during the transfer of the upper from the loading station to the eyeleting station and during the feeding movements of the workholder outwardly for the performance of the eyeleting operation. The supporting device referred to comprises an auxiliary table 314 (Fig. 11) which is located at the side of the eyeleting station toward the loading station, being supported from the eyeleting machine on a bracket 316, and is separated from the eyeleting mechanism feed slide 142 to permit the downwardly projecting heel and side portions of an upper located on the workholder in an outside-up position to be fed outwardly between the eyeleting mechanism and table 314 without interference. Additional support is provided for the outlying toe portions of the upper at the eyeleting station by means of an auxiliary guide 318 in the form of an arcuately bent wire which is mounted on the eyeleting machine feed slide for movement therewith radially outwardly from the turret during the progress of the eyeleting operation. The auxiliary guide 318 is bent to conform substantially to the curvature of the periphery of the turret casing and with the end portion thereof overlying the table 314. During the indexing movement of the turret which carries a workholder and clamped upper

from the loading to the eyeleting station, the outlying toe portions of the upper will be engaged by the table 314 and thereafter by the laterally extending auxiliary guide 318. This support is maintained during the subsequent feeding movement of the workholder outwardly away from the turret by the movement therewith of the guide 318, the end of which continues to ride on the auxiliary table 314.

Referring further to Fig. 11 it will be seen that a similar side table 320 is provided at the right hand side of the lacing mechanism of the machine, being supported from a bracket 324 on the turret casing. The side table 320 is spaced from the lacing machine to permit the side and heel portions of the upper to move between the lacing machine and the side table 320 during the outward feeding movement of the work support at the lacing station. A horizontally disposed arcuate wire guide member 326 is rigidly secured to the lacing machine slide 145 adjacent the turret, and projects from the slide sufficiently so that the end thereof overlies the side table 320. It will readily be appreciated that during the indexing movement of a loaded work support to the lacing station, and subsequently during the outward feeding movement of the workholder, loose portions of the upper will be adequately supported by the side table 320 and also by the arcuate guide member 326 which moves outwardly away from the turret along with the lacing feed mechanism.

Figs. 15 to 21 inclusive illustrate a modification of the shoe upper supporting and clamping device embodying certain additional features of the invention. The improvement shown in these figs. consists of a novel device for detecting and removing from the operating zone of the eyeleting and lacing mechanisms, stray portions of the lining material associated with the shoe upper which might otherwise interfere with the insertion of the initial pairs of eyelets and lacing. This feature of the invention is particularly intended to correct a condition in which the lining assembled with the shoe upper is loosely or improperly trimmed so that the lining overlies that portion of the lacing machine in which the first pair or pairs of eyelets will be placed. In accordance with the invention a modified form of vamp spreader is shown which has been adapted to perform the additional function of engaging and drawing away from the location of the first eyelet pair any overlying or excess portions of the lining of a shoe upper mounted on the machine.

The improved vamp spreader unit shown in Figs. 15 to 21 comprises upper and lower vamp spreaders which are supported in the same manner as the vamp spreaders 147, 148 previously described, to swing about the common pivot 190, and are similarly connected for related movement to engage simultaneously against opposite faces of the vamp portion of the upper. The modified form of the upper vamp spreader for engaging the upwardly turned face of the supported upper (see Figs. 16 and 17) comprises a shank 430 arranged to turn about the horizontal pivot 190 and having at its outer end a flat plate 431 fixed to said shank 430, and a transversely extending vamp engaging arm 432 arranged to turn about a pivotal connection 434 with the plate 431. The lower vamp spreader (see Figs. 16 and 18) similarly comprises a shank portion 435 arranged to turn about the horizontal pivot pin 190 and having fixed at its outer end a flat plate 437, and a laterally extending vamp spreader arm 438 arranged to turn about a pivot 439 on the plate 437. The upper vamp spreader arm 432 is formed with a rearwardly extending tail portion which is connected by means of a tension spring 440 with a lug 442 on the plate 431. The movement of the vamp spreader arm 432 in a clockwise direction about its pivot 434 toward the base of the work support under the influence of spring 440 is limited by the engagement of the butt end of 432 with an offset stop bracket 444 on the plate 431, and by the engagement of the outer edge of said tail portion with a

turned over edge 446 of the plate. The lower vamp spreader is similarly acted upon by a tension spring 448 which is connected between the tail portion of the vamp spreader arm 438 and a lug 450 on the plate 437 which position tends to rock the vamp spreader arm 438 in a clockwise direction to a limiting position in which the tail portion engages a bracket 452 on the shank plate 437 and in which the outer edge of the tail portion engages against a turned over edge 454 of the shank plate 437. 5 The vamp spreader arm 432 has mounted thereon a pair of spring hooks 456 which are arranged for the normally retracted position of the spreader arm 432 of Fig. 17 to hook over the inner edge of the overlying lining material indicated at 457. When, as shown in Figs. 15 to 21 inclusive, the machine is set up for operation upon a shoe upper having the inside lining portion thereof facing upwardly for the insertion of invisible eyelets, a swinging movement of the vamp spreader arm 432 outwardly in a counter clockwise direction from the position shown in 10 Figs. 17 and 21 will cause the hooks 456 to engage with and draw outwardly any overlying or excess portions of the lining as shown for example in Fig. 19, so that this excess lining material is positively removed from the location of the first pair of eyelets. The vamp spreader arm 438 is similarly provided with a pair of hooks 458 which are operative to engage with and draw aside any overlying portions of the lining in a shoe upper placed on the shoe support in an outside-up position for the insertion of 15 visible eyelets. 20 The vamp spreader arms 432 and 438 are moved outwardly so that the hooks 456 and 458 will act to draw aside any stray portions of lining engaged thereby by means of an actuating mechanism which is located at the eyelet station of the machine and which is rendered operative automatically at the start of the eyeleting operation. 25 The vamp spreader arms 432, 438 having been moved to the extended position, shown for example in Figs. 18 and 19, are supported in this position by means of a latching device which is disengaged to permit the return of the vamp spreader arms to the retracted position of Fig. 17 only when the vamp spreaders are again moved to their 30 open work-release position. 35 The device for moving the upper vamp spreader arm 432 outwardly comprises a downwardly curved actuating arm 462 secured to the lower end of a vertical rock shaft 464 mounted in a sleeve bracket 466 on the frame 468 of the eyeleting machine. Rotation of the shaft 464 causes the off-set lower end of the arm 462 to engage against a lip 469 formed on the outer edge of the vamp spreader arm 432 to move the vamp spreader arm outwardly to the position shown in Fig. 19. A laterally extending arm 470 secured to the upper end of rock shaft 464 is connected by a link 472 with an arm 474 connected to the upper end of a vertically disposed control rock shaft 476 which is mounted in bearings formed in the two laterally off-set ends of a vertically disposed bracket 478 secured to the frame of the eyeleting machine. A collar 480 pinned to the rock shaft 476 and arranged to bear against the upper end of the bracket 478, serves to support the shaft vertically in its bearings. The device for moving the lower vamp spreader arm 438 outwardly comprises an actuating arm 482 which is secured to the upper end of a rock shaft 484 mounted in a sleeve bracket 486 on the eyeleting machine frame, and having the off-set upper end thereof arranged for engagement with a downwards turned lip 488 formed in the outer edge of the vamp spreader arm 438. A lever arm 490 secured to the rock shaft 484 is connected by a link 487 with a lever arm 489 fastened onto the vertical control rock shaft 476. These parts are so arranged that a rocking movement of the control rock shaft 476 in a counter-clockwise direction to the position shown in Fig. 15 is effective to cause 40 the actuating arms 462 and 482 to engage with and move 45 50 55 60 65 70 75 80 85 90 95 100

the respective vamp spreader arms 432 and 438 outwardly to the clear position specifically illustrated in Figs. 15, 18, and 19 of the drawings. This rocking movement of the control rock shaft 476 is effected automatically by means of a connection with the starting and stopping control mechanism for the eyeleting machine. An arm 491 secured to the lower end of the vertical control rock shaft 476 is connected by a link 492 to a downwardly extending arm 493 secured to a rock shaft 494 which forms part of the mechanism for throwing the eyeleting machine into operation at the completion of an indexing movement of the work supporting turret of the machine.

The vamp spreader arms 432 and 438 are supported in their extended positions in which the lining engaged by the hooks 456, 458 continues to be held aside, by means of a latch mechanism which automatically locks the vamp spreader arms 432, 438 in their extended positions, and which is released only when the vamp spreaders are moved apart to release the shoe upper. The latch mechanism referred to comprises a pair of spring latches 500 and 502 secured respectively to the tail portions of plates 431 and 437 and which project over the tail portions of the respective vamp spreader arms 432 and 438. The spring latch 500 has secured in the outer end thereof a latch pin 504 which extends downwardly through a notch 506 formed arcuately in the tail portion of arm 432 about the pivotal support 434 as a center, thence downwardly through over-sized holes 508 in the plates 431 and 437, see Fig. 18, and at its lower end bears against the face of the tail portion of the lower vamp spreader arm 438. The latch pin 504 is pressed downwardly by the spring latch 500, so that as the vamp spreader arm 438 is swung outwardly (counterclockwise in Fig. 30), the pin will drop into an aperture 510 in the face of the tail portion of spreader arm 438 to latch the vamp spreader arm 438 in its extended position. Spring latch 502 is secured to the under vamp spreader shank 436 and is arranged to extend outwardly along the underside of the vamp spreader arm 438. At its outer end the spring latch 502 carries a latch pin 512 which extends upwardly through a notch 514 in the tail portion of vamp spreader arm 438 formed arcuately about the vamp spreader arm pivot plate 439 as a center, thence through over-sized holes in the vamp spreader plates 437 and 431, and at its upper end engages against the underside or tail portion of the upper vamp spreader arm 432. An outward movement of the vamp spreader arm 432 about its pivot 434 causes the latch 512 to drop into an aperture 516 in the face of the tail portion of the vamp spreader arm 432. With this construction and arrangement of parts it will be readily appreciated that the latching device acts to latch the respective vamp spreader arms 432, 438 in their relatively extended positions, and that the respective latches are released to permit the return of the vamp spreader arms 432, 438 to their retracted positions under the influence of the springs 440, 448 when the vamp spreaders are moved relatively away from one another to release the finished upper. By such movement the latch pin 504 associated with the upper spring latch 500 is positively withdrawn from the aperture in the lower vamp spreader arm 432, while at the same time the pin 512 in the lower latch 502 is similarly positively moved away from its engaging aperture. The vamp spreader arms 432, 438 released in this manner return to their normal operating position, shown in Fig. 17, under the influence of springs 440, 448.

The operation of the machine will be described in connection with the eyeleting and lacing of a shoe upper supported on a workholder with the lacing margins in an opened out edge-facing relation, and with the outside or finished surface of the upper facing upwardly for the insertion of visible eyelets.

It is assumed that the machine has stopped. The pre-

viously completed upper, eyeleted and laced by the machine is removed by the operator, being drawn outwardly off the work support. The guard 310 serves to guide the heel portion thereof over the inner edge of the retracted lower vamp spreader arm 148 (see Fig. 6). The operator will now make such machine adjustments as may be required in accordance with the style and size of upper about to be placed on the workholder. A measuring bar 149 suitable to the style of shoe upper to be operated upon is mounted on the arm 234 (Fig. 7) and is adjusted for height by manual adjustment of lever 246 and for angle by manual adjustment of the arm 234. The control lever 88 is set for shoe size (see Fig. 12). The workholder 132 at the loading station is fully retracted (see Figs. 1, 3 and 11) being held so by engagement of cam follower member 139 on post 236 with cam slot 140 (see Fig. 7). The gage pins 272 and inner fin 274 mounted on slide 278 on the workholder 132 are located by engagement of follower member 286 (Fig. 9) with the narrow portion of gate cam 285 located in accordance with the setting of the control lever 88 (Figs. 11 and 12). The outer fin 276 mounted on spring plate 300 is spring pressed upwardly into position. The moveable lacing margin clamping jaws 146 have been moved upwardly to an inoperative position to release the completed upper and to permit the insertion of a new upper. The vamp spreaders 147 and 148 are in open position.

In order to load the new shoe upper onto the workholder the operator pushes the shoe upper onto the work support in an upright position with the heel toward the axis of the turret and bent downwardly so that the rail guideways 131 and lower lacing margin clamping jaws including pins 136 of the work holder 132 are projected through the ankle opening of the upper.

The two lacing margins of the upper are placed in edge-facing relation at opposite sides of the fins 274 and 276, and the edges of the ankle opening adjacent thereto are placed against the locating pins 272.

In order to clamp the upper in its adjusted position the operator steps on the foot treadle (not shown) which acts to depress control shaft 156 (Fig. 7) acting through actuating lug 155 and strap 154 to straighten toggle links 151, 152 and thereby to depress the upper lacing margin clamping jaws 146 toward the pins 136. The upper vamp spreader arm 147 is now moved down with sufficient force to engage contact pin 226 and to close the machine starting micro-switch 225, causing the machine to start. The lower vamp spreader 148 is simultaneously moved upwardly so that the outlying portions of the vamp are supported in a horizontal plane between the two vamp spreaders 147, 148. Downward movement of the weighted arm 212 (Figs. 5 and 4) causes toggle links 196, 198 to be moved to a straightened past center locking position.

An indexing movement of the work supporting turret now takes place so that the newly loaded workholder 132 is moved about the turret axis 90 degrees to the eyeleting station. At the eyeleting station the spring plate 300 and outer fin 276 are depressed to inoperative position by engagement with cam 302 (Fig. 7). The cam follower member 139 is aligned with a gateway 141 from the slot 140. The workholder is engaged with the eyeleting feed slide 142 and is given a stepped outward movement for the insertion of successive pairs of eyelets, and is thereafter returned to its starting position preparation for the next succeeding indexing movement of the turret. Inasmuch as the eyeleting machine is similar to that fully described and illustrated in applicant's prior Patent No. 2,461,889 above referred to, no specific description of this operation is included herewith.

For the more adequate support of the vamp portion of the upper when mounted in the machine with the outside surface facing upwardly for the insertion of visible eyelets the vamp portion of the upper is arranged upon approaching the eyeleting station to be en-

gaged upon the support 314 spaced from the eyeleting mechanism, and upon an auxiliary support 318 which is mounted on the feed slide 142 and moves outwardly therewith, so that continued support is provided for the outlying vamp portions of the upper during the eyeleting operation while at the same time space is provided to receive the downwardly extending heel or quarter portions of the upper.

While the several operations are being performed including the eyeleting operation above described at the different operation stations of the machine, the operator will manually remove a completed upper from the next succeeding workholder now located at the loading station, will locate and clamp a new shoe upper in position thereon, and finally will again start the machine in operation in accordance with the procedure above described. The next succeeding indexing movement of the turret causes the workholder 132 and the newly eyeleted shoe upper thereon to be transferred from the lacing station to the eyeleting station where the workholder is engaged with the lacing feed slide 145. At the same time the lacing machine is started in operation so that workholder and associated upper are advanced outwardly for the performance of the series of lacing operations, being thereafter returned to the initial retracted position on the turret.

At the lacing station supporting and guiding devices for the clamped upper are provided, which are similar to those provided at the eyeleting station. As best shown in Fig. 11 these devices include the side table 320 spaced from the feed slide 145 and the curved guide member 326 secured to feed slide 145 for movement therewith and arranged to overlie the side table 320.

In the modified form of the machine illustrated in Figs. 15 to 21, inclusive, a modified form of vamp spreader is employed which comprises the vamp spreader arms 432 and 438 pivotally connected with their shank portions and provided respectively with hook members 456 and 458. The rocking movement of rock shaft 494 to trip the eyeleting machine into operation causes the two actuating arms 462 and 482 to be shifted to engage with and move the respective vamp spreader arms 432, 438 and their associated hook members 456 and 458 outwardly, thus drawing aside any overlying portions of lining which may be picked up by the hooks, as indicated for example in Fig. 19. The spreader arms 432 and 438 are maintained in their extended condition by means of two spring latch arms 500, 502 and latch pins 504, 516 during both the eyeleting and lacing operations.

Upon completion of the lacing operation the feed slide 145 and workholder are returned to their initial starting positions and the machine stops.

During the third and fourth indexing movements of the turret shaft 54 by which the workholder 132 is brought back to its initial loading position the toggle connection 151, 152 holding the clamping jaws 146 in their clamping position is broken, and the toggle connection 196, 198 supporting the vamp spreader arms in their clamping position is also broken so that the lacing margin clamping jaws 146 and the vamp spreaders are moved to the open position to release the eyeleted and laced shoe upper. The clamping jaw toggle links 151, 152, are released as the workholder reaches its third indexed position as shown in Fig. 7 by means of connections which include the plunger 162, slide 164 and actuating arm 184 which as shown in Fig. 12 is given an oscillatory movement in timed relation to each indexing movement by means of a face cam 168 on the drive shaft 182 for the lever drive arm 180 for indexing the turret. The breaking of toggle links 151, 152 acts through the engagement of arms 218, 220 (see Figs. 4 and 6) to break the toggle connection provided by toggle links 196, 198 and thereby to move the vamp spreaders 147, 148 to their open position.

In the event that the vamp spreader construction il-

lustrated in Figs. 15 to 21 inclusive is employed the movement of the vamp spreader arms away from one another acts simultaneously to withdraw the latch pins 508, 514 permitting the vamp spreader arms 432, 438 and associated hooks in 456, 458 to swing inwardly to the normal position shown in Fig. 17.

During the fourth indexing movement of the turret shaft 54 in which the workholder 132 is returned to its initial loading position the follower member 286 associated with slide 278 is engaged by the gate cam 285 and brought into operative relation thereto, so that the location of the pins 272 may be directly controlled by the manual adjustment of control lever 88 in accordance with the size of the next shoe upper to be mounted on the workholder.

Features relating to Lace Measuring Mechanism, Shield Mechanism for Turret Structure, Extra Side Supports for the Turret Structure, Guard in a Lacing Machine, Take-Up Mechanism and Lace Clamping Device have been made the subject matter of divisional applications which were executed as of May 22, 1958 and were forwarded to the United States Patent Office for filing May 23, 1958.

The nature and scope of the invention having been indicated and an embodiment of the invention having been specifically described what is claimed is:

1. In a machine for operating upon shoe uppers having a plurality of shoe upper operating and locating devices at a plurality of stations, a machine base, a work transfer device mounted to rotate about an axis from the base for transferring supported shoe uppers from one to another of said stations which transfer device comprises a rotatable turret small radially as compared with and projecting a substantial distance above said base about which transfer device said stations are grouped, a workholder supported from the turret for movement to successive stations and having cooperating clamping elements spaced for clamping between them the lacing margins of the shoe upper in an opened-out edge-facing relation and with the toe projecting radially outwardly from the turret, and a guideway on which the workholder is movable radially outwardly from its retracted position toward the rotational axis of said turret to a position where it is supported from and extends radially outwardly from the turret, said guideway and workholder while held in said retracted position projecting radially outwardly from the turret to substantially the outer limits of the base, and further being located substantially above said base to permit an upper to be positioned with the inside surface of the vamp facing upwardly and alternatively with the outside surface of the vamp facing upwardly and with the quarter portion of the upper encircling said guideway and holder, and said upper to be moved radially inwardly of the turret for locating the upper with the lacing margins in an opened-out edge-facing position on the workholder.

2. In a machine for operating upon shoe uppers having a plurality of shoe upper locating and operating devices at a plurality of stations, a machine base, a turret mounted from the base about which said stations are grouped comprising a rotatable hub, a guideway supported from and extending radially outwardly from said hub, a workholder slidably supported on the guideway for movement by the turret to different stations and for movement radially outwardly on the guideway from a transfer position on the guideway, said workholder comprising a relatively stationary lower and pivoted upper clamping elements projecting radially outwardly on the workholder, and with the clamping elements and guideway constructed and arranged to extend radially outwardly clear of the turret and supporting base to support the shoe upper with the lacing margins in an opened-out edge-facing relation, alternatively with the outside surface of the vamp facing upwardly and with the quarter portion of the upper

encircling the lower clamping element and guideway, and with the inside surface of the vamp facing upwardly and with the quarter portion of the upper encircling said upper clamping element, means operable at least at one of said stations to move the workholder outwardly on said guideway, and means for locking said workholder in the retracted transfer position during transfer to said station comprising a depending follower member supported from an inwardly disposed portion of said workholder, and a stationary locking groove engaged by said follower having a gate to permit outward movement of the workholder at said station. 10

3. In a machine for operating upon shoe uppers having a plurality of shoe locating and operating devices at a plurality of stations, the combination of a work transfer device which comprises a turret about which said stations are grouped, and a workholder movable by the turret to different stations and movable on the turret radially outwardly from a transfer position on the turret, said workholder comprising upper and lower clamping elements projecting outwardly on the workholder and constructed and arranged to extend radially outwardly clear of the turret and machine to support the shoe upper with the lacing margins in an opened-out edge-facing relation with the outside surface of the vamp facing upwardly and with the quarter portion of the upper encircling the lower clamping element and alternatively with the inside surface of the vamp facing upwardly and with the quarter portion of the upper encircling said upper clamping element, and each of said clamping elements having formed thereon a laterally-extending tongue-engaging guard adapted to engage with and support the tongue of the upper clear of said lacing margins. 25

4. In a machine for operating upon shoe uppers having a plurality of shoe upper locating and operating devices at a plurality of stations, a workholder having mounted thereon cooperating clamping elements for clamping a shoe upper on the workholder with the lacing margin in an opened-out edge-facing relation, means locating said upper in a predetermined relation on the workholder including a shoe upper positioning device movably supported on the workholder for adjustment longitudinally of the lacing margins, means for presenting said workholder in said predetermined relation to the shoe upper locating and operating devices at each of said stations, and a locating device at one of said stations constructed and arranged to control the position of the shoe upper positioning device on the workholder at said station. 40

5. In a machine for operating upon shoe uppers having a plurality of shoe upper locating and supporting devices at a plurality of stations, a work transfer device on which the shoe uppers are transferred from one to another of said stations, a workholder mounted on the transfer device having mounted thereon cooperating clamping elements for clamping a shoe upper on the workholder with the lacing margins in an opened-out edge-facing relation, means locating said upper in a predetermined relation on the workholder including ankle edge engaging elements and a lacing margin separating fin movably mounted on the workholder for movement longitudinally of the lacing margins, means presenting said workholder in a predetermined relation to each of said devices at the respective stations, and a locating device at one of said stations constructed and arranged to control the position of the shoe upper locating means on the workholder at said station. 50

6. In a machine for operating upon shoe uppers having a plurality of shoe upper locating and operating devices at a plurality of stations, a work transfer device on which the shoe uppers are transferred from one to another of said stations, a workholder mounted on the transfer device having mounted thereon cooperating clamping elements for clamping a shoe upper on the workholder with the lacing margins in an opened-out edge-facing relation, 70

means locating said upper in a predetermined relation on the workholder including a lacing margin separating fin spring supported from the work transfer device to engage a portion of the lacing margins adjacent the toe of the upper, and a slide mounted on the workholder for movement longitudinally of the lacing margins having mounted thereon ankle edge engaging gauge pins and a second lacing margin separating fin adjacent thereto, means presenting said workholder in a predetermined relation to each of said devices at the respective stations, and a locating device at one of said stations constructed and arranged to control the position of the slide on the workholder at said station. 75

7. In a machine for operating upon shoe uppers having a plurality of shoe upper locating and operating devices at the respective stations, a work transfer device on which the shoe uppers are transferred from one to another of said stations, a workholder having mounted thereon cooperating clamping elements for clamping a shoe upper on the workholder with the lacing margins in an opened-out edge-facing relation, means locating said upper in a predetermined relation on the workholder including a slide, and ankle edge engaging elements, and a lacing margin separating fin mounted on the slide for movement on the workholder longitudinally of the lacing margins, a second lacing margin separating fin mounted on the work transfer device, means presenting said workholder in a predetermined relation at each of said devices at the respective stations, and a locating device at one of said stations constructed and arranged to control the position of the slide with the fin and ankle edge engaging elements thereon at said station. 20

8. In a machine for operating upon shoe uppers having a plurality of shoe upper locating and operating devices at a plurality of stations, a work transfer device for transferring supported shoe uppers from one to another of said stations which comprises a turret about which said stations are grouped, a guideway mounted on the turret extending radially outwardly with respect to the turret axis, and a workholder movably supported on the guideway having mounted thereon cooperating clamping elements for clamping a shoe upper on the support with the lacing margins in an opened-out edge-facing relation and with the ankle and heel portions of the upper disposed toward the axis of said turret, the combination of a shoe upper positioning device having a shoe upper margin engaging element movably positioned on the workholder for locating the shoe upper on the workholder, and a locating device at one of said stations constructed and arranged to control the position of the shoe upper positioning device on the workholder at said station. 45

9. In a machine for operating upon shoe uppers having a plurality of shoe upper locating and operating devices at a plurality of stations, a work transfer device for transferring supported shoe uppers from one to another of said stations which comprises a turret about which said stations are grouped, a guideway mounted on the turret extending radially with respect to the turret axis, and a workholder movably supported on the guideway having mounted thereon cooperating clamping elements for clamping a shoe upper on the support with the lacing margins in an opened-out edge-facing relation and with the ankle and heel portions of the upper disposed toward the axis of said turret, the combination of a shoe upper positioning device comprising a slide mounted on the workholder to move longitudinally of the guideway, a shoe upper margin engaging element on the slide against which the shoe upper is positioned longitudinally of the guideway on the workholder, and a locating device at one of said stations constructed and arranged to control the position of the shoe upper positioning device on the workholder at said station. 55

10. In a machine for operating upon shoe uppers having a plurality of shoe upper locating and operating devices at a plurality of stations, a work transfer device 75

for transferring supported shoe uppers from one to another of said stations which comprises a turret about which said stations are grouped, a guideway mounted on the turret extending radially with respect to the turret axis, a workholder movably supported on the guideway to be presented in operating relation to said devices at each of said stations and having mounted thereon cooperating clamping elements for clamping a shoe upper on the support with the lacing margins in an opened-out edge-facing relation and with the ankle and heel portions of the upper disposed toward the axis of said turret, a shoe upper positioning device comprising a slide movable on the workholder longitudinally of the guideway, and a shoe upper margin engaging element on the slide against which the shoe upper is positioned longitudinally of the guideway on the workholder, a cam follower supported from the slide, a gate cam adjustably supported on the turret for engagement with said follower to position the follower and slide at the locating station, and means under the control of the operator for adjusting the gate cam.

11. In a machine for operating upon shoe uppers having a plurality of shoe upper locating and operating devices at a plurality of stations, a work transfer device for transferring supported shoe uppers from one to another of said stations which comprises a turret about which said stations are grouped, a guideway mounted on the turret extending radially with respect to the turret axis, a workholder movably supported on the guideway having mounted thereon cooperating clamping elements for clamping a shoe upper on the support with the lacing margins in an opened-out edge-facing relation and with the ankle and heel portions of the upper disposed toward the axis of said turret, a shoe upper positioning device comprising a slide adjustable on the workholder longitudinally of the guideway, gauging surfaces and a margin separating fin for engagement with the edge portions of the upper at the ankle end of said lacing margins on the slide, a second lacing margin engaging fin arranged to engage a portion of the lacing margins toward the toe of the upper, and means on the turret for supporting said second fin, and a locating device constructed and arranged to control the position of the slide with the fin and engaging surfaces on the workholder at the locating station.

12. In a machine for operating upon shoe uppers having a plurality of shoe upper locating and operating devices at a plurality of stations, a work transfer device for transferring supported shoe uppers from one to another of said stations which comprises a turret about which said stations are grouped, a guideway mounted on the turret extending radially with respect to the turret axis, a workholder movably supported on the guideway comprising cooperating clamping elements for clamping a shoe upper on the support with the lacing margins in an opened-out edge-facing relation and with the ankle and heel portions of the upper disposed toward the axis of said turret, a shoe upper positioning device comprising a slide supported from the turret with relation to the guideway and workholder for adjustment longitudinally of the guideway, gauging surfaces and a margin separating fin supported on the slide for engagement with edge portions of the upper adjacent the ankle end of the lacing margins, a second lacing margin engaging fin arranged for engaging a portion of said margins toward the toe of the upper, means mounted from the turret for supporting said second fin normally in engaging position with said margins, a locating device constructed and arranged to control the position of the slide with the fin and engaging surfaces longitudinally of the guideway and workholder at the locating station, and control means acting upon said second fin supporting means upon movement of the workholder to each successive operating station to move the said second fin away from said upper margin engaging position.

13. In a machine for operating upon shoe uppers hav-

ing a plurality of shoe upper locating and operating devices at a plurality of stations, a work transfer device which comprises a turret rotatable to transfer an upper to successive stations, a guideway disposed radially from the turret, a workholder movable on said guideway comprising cooperating clamping elements for clamping an upper on the workholder with the lacing margins in an opened-out edge-facing relation and with the ankle and heel portions of the upper disposed toward the axis of said turret, a locating device for locating the lacing margins of the upper on the workholder including a gauging element slidably mounted on the workholder for adjustment longitudinally of said guideway having a margin-separating fin and gauging surfaces for engagement with the ankle portions of the upper adjacent said lacing margins, a second margin-positioning fin spring-supported from the turret beneath the guideway for engagement with portions of said margins toward the toe of the upper, means under the control of the operator for positioning said gauging element to locate the upper at the locating station, and devices operable upon movement of the workholder to each successive operating station to move the spring supported fin out of engagement with the upper.

14. In a machine for operating upon shoe uppers having a plurality of shoe upper locating and operating stations, a work transfer device which comprises a turret having a rotatable central shaft, a table on the shaft, and a guideway extending radially outwardly from the table providing heel clearance beneath the guideway and table for the encircling heel portion of an upper, a workholder slidably supported on the guideway, having clamping elements arranged to support the upper with the lacing margins in an opened-out edge-facing relation, a locating device for locating the lacing margins of the upper on the work support including a gauging element supported from the turret with relation to the guideway and workholder to slide longitudinally thereof, an adjustable gate cam supported from the machine beneath said table, a follower element carried by the gauging element for engagement with said cam, means under the control of the operator for adjusting the position of said gate cam radially of the turret at the loading station, a fin spring supported from the turret for engagement with the edges of the lacing margins, and devices rendered operative by rotation of the turret to move said fin away from the shoe upper at each of said operating stations.

15. In a machine for operating upon shoe uppers, the combination of a workholder, means on the workholder for clamping the upper with the lacing margins in an opened-out edge-facing relation, and a vamp spreader comprising a pair of clamping elements movably supported from the workholder and movable respectively from positions spaced from the workholder above and below the clamped upper into a clamping position to clamp between them the outlying portions of the vamp in said opened-out position.

16. In a machine for operating upon shoe uppers, the combination of a workholder, means on the workholder for clamping the lacing margin portions of the upper in an opened-out edge-facing relation, and a vamp spreader comprising a pair of clamping elements supported from the workholder and movable respectively from positions spaced from the workholder above and below the clamped upper into a clamping position to clamp between them the outlying portions of the vamp in said opened-out position, and operating means connecting said clamping elements for movement simultaneously to and from clamping position.

17. In a machine for operating upon shoe uppers, the combination of a workholder, means on the workholder for clamping the lacing margin portions of the upper in an opened-out edge-facing relation, a vamp spreader comprising a pair of clamping elements supported to turn on a common pivot on the workholder into clamping engagement with opposite sides of outlying portions of the vamp

in said opened-out position, a pair of toggle links connected respectively with said clamping elements, a pivot connecting said links, and means to guide said pivot along a predetermined path for effecting a simultaneous movement of said clamping elements to and from said clamping position.

18. In a machine for operating upon shoe uppers, the combination with a guideway, of a workholder adapted to be advanced on the guideway into the machine, there being a device on the workholder for clamping an upper with the lacing margins in an opened-out edge-facing relation and with the vamp portion thereof projecting into the machine, and a vamp spreader comprising a pair of clamping elements movably supported from the workholder for movement from positions spaced from opposite sides of the workholder and from opposite sides of the upper for clamping therebetween outlying portions of the vamp in said opened-out position.

19. In a machine for operating upon shoe uppers the combination with a guideway, of a workholder adapted to be advanced on the guideway into the machine, which comprises on the workholder parallel supporting elements, and cooperating clamping elements for clamping the lacing margin portions of the upper therebetween in an opened-out edge-facing relation and with the vamp portion of the upper extending into the machine, a vamp spreader comprising a pair of clamping elements supported to turn on a common pivot on the workholder from positions from opposite sides of the workholders into clamping engagement with opposite sides of outlying portions of the vamp in said opened-out position, and means moving said clamping element simultaneously to and from said clamping position.

20. In a machine for operating upon shoe uppers the combination of a workholder, means on workholder for clamping the lacing margin portions of the uppers in an opened-out edge-facing relation, a vamp spreader comprising a pair of clamping elements pivoted on the workholder to turn into clamping engagement with opposite sides of outlying portions of the vamp in an opened-out position, a pair of toggle links connected respectively with said clamping elements, a pivot movable between broken and a beyond center locked spreader clamping position, means to guide said pivot along a predetermined path for effecting simultaneous movement of said elements to and from said clamping position, and a weighted arm connected to said toggle links and rendered operative between clamping movement of the clamping elements to move the toggle links to the locking position.

21. In a machine for operating upon shoe uppers, having shoe locating and operating mechanisms at different loading and operating stations, a transfer device which comprises a turret rotatable between upper successive stations, a guideway disposed radially from the turret, and a workholder slidably supported on the guideway to be presented in operative relation to the mechanism at each of said stations and comprising movable clamping members for clamping the lacing margin portions of the upper in an opened-out edge-facing relation and with the quarter portion of the uppers placed toward the axis of the turret, toggle means connected between the workholder and said members having a straightened shoe upper clamping position, a vamp spreader comprising a pair of clamping elements pivoted on the workholder to turn into clamping engagement with opposite sides of outlying portions of the vamp in an opened-out position, a pair of toggle links connected between said clamping elements and movable to a beyond-center locked spreader-clamping position, a pivot connecting said toggle links, and means to guide said pivot along a predetermined path of said links between broken positions of toggle links.

22. In a machine for operating upon shoe uppers, having shoe locating and operating mechanisms at different stations, a transfer device which comprises, a turret rotatable to transfer an upper to successive stations, a guide-

way disposed radially from the turret, and a workholder slidably supported on the guideway to be presented in operative relation to the mechanism at each of said stations and comprising cooperating pairs of clamping elements spaced from one another for clamping the lacing margin portions of the upper in an opened-out edge-facing relation and with the quarter portion of the upper placed toward the axis of the turret, a vamp spreader comprising a pair of clamping elements pivoted on the workholder for movement from positions spaced from opposite sides of the workholder to permit the quarter to be positioned over the workholder in encircling relation therewith toward and away from a clamping relation with one another and having transverse vamp supporting surfaces arranged to engage the vamp and toe portions of the upper therebetween, and means for imparting co-operating movements to said vamp spreaders to and from the clamping relation with the upper.

23. In a machine for operating upon shoe uppers, the combination with a guideway of a workholder adapted to be advanced on the guideway into the machine which comprises cooperating pairs of clamping elements providing two parallel elongated areas of clamping contact with the upper spaced from one another for clamping the lacing margins of the upper in an opened-out edge-facing relation, a pair of vamp spreader arms pivoted on a portion of the workholder beyond that on which is located the quarter portion of the clamped upper and having transverse vamp supporting surfaces arranged to engage the vamp and toe portions of the upper therebetween in said opened-out relation, and an operating device connecting said vamp spreaders for simultaneous movement from positions spaced at opposite sides of the workholder to permit the quarter portion of an upper to be placed in encircling relation to the workholder toward and away from a clamping relation to one another to clamp and to release the vamp portion of the upper.

24. In a machine for operating upon shoe uppers, a workholder which comprises cooperating pairs of clamping elements providing two parallel elongated areas of clamping contact with the upper spaced from one another for clamping the lacing margins of the upper in an opened-out edge-facing relation, a pair of vamp spreaders having transverse vamp supporting surfaces arranged to engage the vamp and toe portions of the upper therebetween, supporting pivots for the vamp spreaders on the workholder on which the vamp spreaders are movable toward and away from clamping relation to one another, and means for imparting co-ordinated clamping and releasing movements to said vamp spreaders comprising a pair of toggle links connected with the respective spreaders and movable to a beyond center locked spreader clamping position, and a weighted arm connected to one of said toggle links and rendered operative by the clamping movement of the vamp spreaders to move the toggle links to the locking position.

25. In a machine for operating upon shoe uppers, a workholder for supporting a shoe upper with the lacing margins in an opened-out edge-facing relation, a vamp spreader pivotally supported on the workholder for movement against the shoe upper comprising a shank element pivoted on the workholder for movement toward and away from the upper, a vamp spreader arm mounted from the shank element and extending laterally across the vamp portion of the shoe upper, a pivot connecting the shank and vamp spreader arm on which the arm moves outwardly in a direction substantially parallel to the supported upper, a hook device on the vamp spreader arm disposed to hook into portions of lining overlying the lacing margins, and means for moving the said arm and hook device associated therewith outwardly about its pivot to clear such portions of the upper from the lacing machine.

26. In a machine for operating upon shoe uppers having a shoe upper eyeleting mechanism, a guideway, and a workholder supported on the guideway for movement to

ward the eyeleting mechanism and adapted to support a shoe upper on the support with the lacing margins in an opened-out edge-facing position, the combination of a hook device supported on the workholder for movement to engage with and clear overlying portions of the lining from the lacing margins of the supported upper, and means acting in advance of the eyeleting mechanism for moving said device to clear the said portions of the lining.

27. In a machine for operating upon shoe uppers, a workholder for supporting a shoe upper with the lacing margins in an opened-out edge-facing relation, a vamp spreader engaging the shoe upper comprising a shank member pivoted on the workholder for movement against the upper, a vamp spreader arm pivoted on the shank and extending transversely across the vamp portion of the shoe upper, means holding the arm yieldably in a retracted position toward the shank, a hook device on the vamp spreader arm disposed for holding said retracted position of the vamp spreader arm to hook over any portions of the lining overlying the lacing margins, an actuating member moving about a relatively stationary pivot arranged for one position of the workholder to engage with and move the arm and hook associated therewith outwardly about said pivot to clear portions of the upper from the lacing margins.

28. In a machine for operating upon shoe uppers having a shoe upper eyeleting mechanism, a guideway, and a workholder supported on the guideway for movement toward the eyeleting mechanism and adapted to support a shoe upper with the lacing margins in an opened-out edge-facing relation, the combination of a vamp spreader comprising a shank element pivoted on the workholder for movement against the supported upper, a vamp spreader arm extending transversely across the vamp pivotally supported from the shank for movement outwardly in a plane substantially parallel to the supported upper, a hook device mounted on the vamp spreader arm to hook into portions of the lining overlying the lacing margins, spring means maintaining the vamp spreader arm in a retracted position toward the shank element, and an actuating element supported from the eyeleting machine operable to engage with and move the vamp spreader arm outwardly, and means controlled from the eyeleting machine for actuating said actuating element to clear the lining from the lacing margin in advance of the eyeleting operation.

29. In a machine for operating upon shoe uppers having a shoe upper eyeleting mechanism, guideway, and a workholder supported on the guideway for movement toward the eyeleting mechanism and adapted to support a shoe upper with the lacing margins in an opened-out edge-facing relation, the combination of a vamp spreader comprising a shank element pivoted on the workholder for movement toward the supported upper, a vamp spreader arm extending transversely across the vamp spreader supported from the shank for movement outwardly over the vamp, a hook device on the workholder rendered operative by the said outward movement to hook into portions of the lining overlying the lacing margins, yieldable means maintaining the vamp spreader arm normally in a retracted position toward the shank element, a device controlled from the eyeleting mechanism in advance of the eyeleting operation to engage in and move the vamp spreader arm outwardly, and a latch operable to maintain the arm in said outward position.

30. A vamp spreader for use with a workholder adapted to support the shoe upper with the lacing margins in an opened-out edge-facing relation, which comprises a shank element pivoted on the workholder to turn against the supported shoe upper, a vamp spreader arm extending transversely across the vamp portion of the shoe upper, a pivot on the shank element on which

said arm swings outwardly and away from the shank, spring means connected between the shank element and arm tending to move the arm against the shank element, said shank element and arm having engaging surfaces limiting said movement of the arm, and a hook device on the vamp spreader arm rendered operative by said outward movement of the arm to hook into and clear from the lacing margins overlying portions of the lining.

31. A vamp spreader for use with a workholder adapted to support a shoe upper with the lacing margins in an opened-out edge-facing relation, which comprises a shank element pivoted on the workholder to turn against the supported shoe upper, and having at its outer end a pivot plate lying substantially in a plane parallel to the supported upper, a vamp spreader arm extending transversely across the vamp portion of the shoe upper and pivotally connected to turn on said pivot plate, spring means connected between the shank element and arm urging the arm toward the shank element, said shank and arm having stop surfaces arranged to limit the movement of the arm toward the shank element, a pair of hook elements supported on the arm to hook into any portion of lining overlying said eyelet margins.

32. A vamp spreader for use with a workholder to support a shoe upper with the lacing margins in an opened-out edge-facing relation, which comprises a pair of shank elements pivoted on the workholder to turn against opposite sides of the shoe upper, a vamp spreader arm associated with each shank element extending transversely across the vamp portion of the shoe upper and pivotally connected with the respective shank elements for an outward-swinging movement relative to the shank element, hook devices supported from each of said arms disposed over the lacing margins of the shoe upper to be rendered operative by said swinging movement to draw aside overlying portions of the lining.

33. A vamp spreader for use with a workholder to support a shoe upper with lacing margins in an opened-out edge-facing relation which comprises a pair of shank elements supported to turn about a common pivot on the workholder against opposite sides of the supported upper, toggle connections connecting said shank elements for simultaneous movements against and away from the supported upper, a vamp spreader arm associated with each shank element extending transversely across the vamp portion of the shoe upper and pivotally connected with the respective shank elements for movement in a plane substantially parallel with the supported upper outwardly from the shank element, spring means connected between each arm and the respective shank elements urging the respective arms toward the shank elements and hooks associated with said arms disposed over the lacing margins to be rendered operative by an outward movement of the arm to engage and draw aside overlying portions of lining material.

34. In a machine for operating upon shoe uppers, a turret adapted for indexing movements to a plurality of operating stations about the turret, an eyeleting mechanism at one of said stations, a workholder on the turret movable to said different operating stations arranged to support the shoe upper with the lacing margins in an opened-out edge-facing relation, a vamp spreader which comprises a shank element pivoted on the workholder for movement against the supported upper, a vamp spreader arm extending transversely across the vamp pivotally supported on the shank for movement outwardly from the shank element, spring means connected between the shank element and arm urging the arm toward the shank element, a hook device on the arm rendered operative by said outward movement of the arm to engage and clear overlying portions of the lining from the lacing machine, an actuating element movably supported on the machine at the eyeleting station to engage with and move said vamp spreader arm outwardly,

29

means acting automatically in advance of the eyeleting operation for moving said actuating element to move the vamp spreader arm outwardly, a latch rendered operative by the outward movement of the vamp spreader arm to latch said arm in the outward position, and means 5 acting when rendered operative to automatically trip the latch.
